AIR CONDITIONING DUCT

Richard L. Hull, Davenport, Iowa, assignor to Ametek,
Inc., New York, N.Y., a corporation of Delaware

Filed Feb. 26, 1965, Ser. No. 83,996

Term of patent 14 years

(Cl. D62—4)

FIG. 2

FIG. 1

FIG. 1 is a perspective view of the air conditioning duct.

FIG. 2 is a side view of the air conditioning duct of FIG. 1.

FIG. 3 is a perspective view with one of the cone plates removed.

The broken line disclosure of a duct in FIG. 1 is for illustrative purposes only.

The characteristic features of my design reside primarily in the shape and configuration of the air inlet opening with one end thereof being flattened and one corner at the said flattened end being inset and partially blocked off to provide a sweeping curved edge portion thereat, all as shown.

What is claimed is:

The ornamental design for an air conditioning duct, substantially as shown and described.
